F. L. Scott, Inventor,
By his Attorney, Jessie R. Stone

UNITED STATES PATENT OFFICE.

FLOYD L. SCOTT, OF HOUSTON, TEXAS.

LUBRICATOR.

1,373,026.

Specification of Letters Patent. Patented Mar. 29, 1921.

Application filed August 21, 1920. Serial No. 405,181.

To all whom it may concern:

Be it known that I, FLOYD L. SCOTT, a citizen of the United States, residing at Houston, Harris county, Texas, have invented a certain new and useful Improvement in Lubricators, of which the following is a full, clear, and exact description, such as will enable others skilled in the art to which it appertains to make and use the same.

My invention relates to an improvement in lubricators designed especially for use in connection with earth boring drills employed in deep well drilling.

It has been found essential to provide a lubricating means for earth boring drills of the roller type employed in well drilling, and that some pressure means must be employed to force the lubricant from the lubricator to the bearings of the rolling cutters upon the drill in order to obtain efficient lubrication thereof. This is due largely to the fact that in the use of earth boring drills flushing water is pumped downwardly through the drill stem and the bit against the cutters and the portion of the well upon which they operate, so as to flush the cuttings away from the drill and carry them in suspension upwardly to the surface. The drill is, therefore, working constantly in a head of water and mud which exerts a backward pressure through the bearings against the lubricant and if force is not employed upon the lubricant it will not find its way to the bearings in the manner desired.

An object of my invention is to provide a lubricator for use on drills of this type wherein the pressure of the flushing water will act to force the lubricant to the bearings without danger of the flushing water and sediment carried therewith finding its way with the lubricant to the bearings.

Another object is to provide a lubricator of the type described in which the force of the flushing water within the drill stem will be exerted directly against a collapsible container, in which the lubricant is held, with a practically continuous pressure. Further objects and advantages will appear in the description which follows.

Referring to the drawing forming a part

of this specification, and wherein a preferred embodiment of my invention is disclosed, Figure 1 is a central longitudinal section through my improved lubricator, and Fig. 55 2 is a transverse section thereof on the plane 2-2 of Fig. 1. Like numerals of reference are applied to like parts in both the views.

The lubricator disclosed in the drawing is adapted to be used upon roller bits of the type disclosed in the patent to H. R. Hughes, No. 1,174,575, patented March 7, 1916. The device comprises a length of pipe 1, constituting a barrel surrounding the lubricant container, said barrel being threaded at the lower end for attachment to a coupling 2, said coupling being threaded 60 interiorly at the lower end at 3 for attachment to the nipple at the upper end of the drill. The coupling 2 has a central channel 70 4 therethrough, which may be closed by means of a valve 5, said valve being rotated by means of a squared end 6, which may be gripped by means of a wrench.

The upper end of the barrel 1 is threaded 75 to provide attachment for a cap 7, said cap fitting over the upper end of the barrel and provided with a central opening 8 therethrough to receive the upper end of the attaching member 9. The attaching member 80 9 is tubular and has a central passage 10 therethrough, and is closed at the upper end by means of a cap 11. The upper end of the attaching member 9 is threaded to receive a nut 12 which bears against the upper 85 face of the cap 7. An annular shoulder 13 is formed centrally of the attaching member, said shoulder forming with the nut 12, a means to secure the said attaching member to the cap 7, as shown in the drawing. The 90 lower end of the attaching member has formed thereon annular corrugations 14 for the better attachment of a collapsible lubricant container 15.

The coupling 2 is provided with a countersunk threaded recess 20 inside the lubricator barrel 1, in which recess is screwed a lower attaching coupling 16, the upper end of which is reduced in diameter and provided with annular corrugations 14' to receive the lower end of the collapsible lubricant container 15. At the lower end of the

attaching coupling 16, the passage therethrough is preferably covered by means of a perforated diaphragm 17, which acts as a sort of strainer for the lubricant, as will 5 be obvious.

The lubricant container 15 may be made of rubber hose of durable construction or of canvas or other similar material, which must be flexible and also fluid tight and 10 easily collapsible. The upper end of this container is secured to the tubular attaching member 9 by any suitable means, but I have shown it as being wound with a strong wire 15 which acts to clench the collapsible tube against the corrugated surface of the attaching member. The lower end is also secured to the lower attaching coupling 16 in the same manner, the method used being such as to provide a fluid tight connection 20 at both ends of the container. The lubricator barrel 1 has perforations 19 therein, both at the upper and lower ends thereof, to allow the entrance to the said barrel of the flushing fluid pumped downwardly 25 through the drill stem within which this lubricator is seated. The lower holes are provided to drain the barrel when the lubricator is not in use.

In the use of this device, the same is 30 screwed at its lower end upon an up-standing nipple on the drill, to which it is to be attached, the valve 6 being closed until it is desired to insert the drill within the well, at which time the valve will be opened to allow 35 the flow of lubricant to the bit. The lubricator is assembled by first screwing the attaching coupling 16 within the coupling 2. The lubricant container 15 will then be secured firmly thereto and at its upper end 40 will be attached to the attaching member 9. The lubricator barrel 1 will then be fixed in position and the cap 7 inserted downwardly over the upper end 9 of the attaching member and the nut 12 used to tighten the attaching member firmly to the cap. The lubricant will be then poured into the upper end of the lubricator chamber and when the device has been filled the cap 11 will be 45 screwed firmly in position. The device is then ready to be inserted within the well.

The flushing fluid used in rotary drilling operations is pumped downwardly through the drill stem and through small channels in the drill against the cutters and the bottom of the hole. The pressure of the fluid within the drill stem is greater than the pressure outside of the drill stem, due to the force of the pump which is stronger within the drill stem than outside thereof. The 50 force of the water within the drill stem is exerted through the openings 19 in the lubricator barrel directly against the sides of the collapsible lubricant container 15, thus acting to exert its pressure directly against 55 the lubricant within the collapsible con-

tainer, forcing it downwardly through the channel 4 to the bit. It is obvious that the water, which is usually accompanied by quantities of mud and sediment, will not be able to find entrance to the lubricant chamber and can not thus be forced downwardly against the bearings of the drill. At the same time the full pressure of the water will be exerted upon the lubricant and will act to drive it downwardly to the bearings 70 against the pressure of the head of water outside the bearings. The advantages of this type of lubricator over the old type of lubricator, having the water pressure exerted directly upon the lubricant or against 75 a piston on top thereof, are readily apparent. The water will find entrance, in the old type of lubricator, past the piston to the lubricator, and thus pass directly to the bearings, but in my improved type of lubricant container, this action is impossible. 80

Having thus described my invention, what I claim as new and desire to protect by Letters Patent is:

1. A lubricator comprising a barrel, a connecting member in the lower end thereof, a second connecting member at the upper end thereof, a flexible lubricant container between said connecting members, said barrel being perforated to allow hydraulic pressure 90 to be exerted directly upon said container.

2. A lubricator comprising a supported barrel, connecting members at the upper and lower ends thereof and a compressible lubricant container secured within said barrel, in fluid tight relation with said connecting members, said barrel being perforated to 100 allow the entrance of fluid therethrough.

3. A lubricator, comprising a coupling, a perforated barrel attached thereto, a connecting member at the upper end of said barrel and extending downwardly therein, a second attaching member inside the lower end of said barrel, and a flexible lubricant container secured to said attaching members 105 and forming with said attaching members a fluid tight connection.

4. A lubricator comprising a flexible tube, means to close the upper end thereof, means outside said tube to support said tube in 115 erect position and means to attach the lower end thereof to the tool to be lubricated.

5. A lubricator comprising a flexible tube closed at one end, a rigid supporting barrel, and a coupling secured to said tube and barrel for attachment to the tool to be lubricated, said barrel being perforated to admit hydraulic pressure to the outer surface of the said tube. 120

6. In a pressure-operated lubricator, a 125 flexible tube for lubricant, a perforated supporting barrel outside thereof, a closure for one end of said tube, and a coupling at the other end for the purpose described.

7. In a hydraulic pressure-operated lubri- 130

cator, a flexible lubricant container, means to support said container in extended position, whereby the walls thereof are exposed to water pressure, means to close one end 5 thereof and serving also to attach said container to said supporting means, and an attaching means at the opposite end having

a lubricant passage therethrough to the bearings to be lubricated.

In testimony whereof, I hereunto affix my signature, this the 13th day of August, A. D. 1920.

FLOYD L. SCOTT.
